(57) **CLAIM**

The ornamental design for a scissor-type holder and grip elements for securing and crushing crustacean shells, food bones, and the like, as shown and described.

DESCRIPTION

FIG. 1 is a front elevation view of a scissor-type holder and grip element for securing and crushing crustacean shells, food bones, and the like, showing my design;
FIG. 2 is a left side elevation view thereof;
FIG. 3 is a top plan view thereof;
FIG. 4 is a right side elevation view thereof;
FIG. 5 is a rear elevation view thereof; and,
FIG. 6 is a bottom view thereof.
